US0D1106677S

(12) **United States Design Patent** (10) **Patent No.:** **US D1,106,677 S**
(45) **Date of Patent:** **** Dec. 23, 2025**

(54) **TROLLEY CASE**

(71) Applicant: **Zixi Guan**, Taizhou (CN)

(72) Inventor: **Zixi Guan**, Taizhou (CN)

(**) Term: **15 Years**

(21) Appl. No.: **29/996,866**

(22) Filed: **Apr. 3, 2025**

(51) **LOC (15) Cl.** **03-01**

(52) **U.S. Cl.**

USPC **D3/281**; D3/279; D3/302; D3/305

(58) **Field of Classification Search**

(57) **CLAIM**

The ornamental design for a trolley case, as shown and described.

DESCRIPTION

FIG. 1 is a first perspective view of a trolley case showing my new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of an in-use state of the trolley case of FIG. 1.

The broken lines and the lightened spaces within depict portions of the trolley case that form no part of the claimed design.

1 Claim, 9 Drawing Sheets
